UNITED STATES PATENT OFFICE.

JOHN L. ALKIRE, OF DENVER, COLORADO.

PENCIL-SHARPENER.

1,119,788.

Specification of Letters Patent.

Patented Dec. 8, 1914.

Application filed April 22, 1913. Serial No. 762,880.

To all whom it may concern:

Be it known that I, JOHN L. ALKIRE, a citizen of the United States, residing at Denver, in the county of Denver and State 5 of Colorado, have invented certain new and useful Improvements in Pencil-Sharpener, of which the following is a specification.

This invention relates to pencil sharpeners and more particularly to sharpeners of the 10 type illustrated in my United States Letters-Patent No. 1,051,658, issued January 28, 1913.

The objects of the present invention reside in the provision of several improvements 15 which many experiments have demonstrated to be of value in an article of this character and principal among which are a simplification of the construction of the cutting member and of the method of securing the same 20 to the sheath into which in practice, the pencil is inserted, the provision of a spring clip for securing the sheath together with a pencil inserted therein to the pocket of a garment, a modification of the construction 25 of the resilient means provided for pressing a pencil against the cutting edge of the chisel of the article and for holding the latter in its adjusted position on a pencil, and a contraction of the ends of the sheath 30 whereby a pencil may be moved longitudinally through the same without coming in contact with the cutting edge of the chisel.

A sharpener in which the above enumerated improvements are embodied has been 35 illustrated in the accompanying drawings in the various views of which like parts are similarly designated, and in which,

Figure 1 represents a plan view of the improved sharpener, Fig. 2, a side elevation 40 of the same with a pencil in the position in which it is held while being pointed, Fig. 3, a longitudinal section through the sharpener in the position it occupies on a pencil when not in use, Fig. 4, a side elevation of 45 the article showing a modified form of construction of the spring clip and springs included therein, and Fig. 5, a transverse section taken along the line 5—5, Fig. 4.

My improved pencil sharpener is like that 50 shown in the above mentioned patent, composed of two co-operative members one of which consists of a sheath made of brass or other suitable metal, into which in practice, the pencil is inserted, while the other com- 55 prises a chisel of hardened steel which is removably attached to the sheath to point a

pencil drawn across the cutting edge formed at an end thereof. The sheath which in the drawing is designated by the numeral 2, is of cylindrical form and open at its ends. It 60 has a longitudinal slot 3 the edges of which are formed and bent to provide three pairs of oppositely disposed lips which co-operatively secure the chisel in its proper position with relation to the sheath, and a mouth 65 4 into which the end of the pencil is inserted while it is being pointed by drawing it across the cutting edge of the said chisel. One of the pair of lips 5 is disposed at an extremity of the sheath, another pair 6, is 70 formed adjacent the mouth 4 and obliquely with relation to the longitudinal axis of the sheath for the purpose of holding the cutting edge of the chisel in the proper position to perform its function, while the third pair 75 of lips 7, is disposed intermediate of the others in a plane nearer the axis of the sheath to provide a support for the cutting member placed beneath the outer pairs.

The sheath 2 is provided opposite to its 80 slot 3 with a longitudinal slot 8 of shorter length through which projects a spring 9 made of a separate piece of tempered steel which at one of its ends is secured to the sheath by solder or other suitable means as 85 at 10. The sheath is furthermore provided at its end remote from that at which the spring 9 is fastened, with an integral, resilient clip 12 the end of which bears against the free extremity of the spring 9. The two 90 resilient members 12 and 9 of the device co-operate to press a pencil against the cutting edge of the chisel during the process of pointing the same, as shown in Fig. 2, or to clamp the sheath in its adjusted position on the pencil 95 when the sharpener is not in use, as is illustrated in Fig. 3. When the sheath is in the last mentioned position on the pencil, the clip 12 provides an efficient means for securing both the sharpener and the pencil 100 to the pocket of a garment in which the latter is carried.

The cutting member of the sharpener consists of a transversely curved chisel 13 of hardened steel which normally is placed underneath the outer pairs of lips 5 and 6 and upon the intermediate pair 7, with the cutting edge 14 formed at one of its ends, extending into the mouth 4. The end of the chisel opposite to its cutting edge is curved 110 preferably in the manner shown at 15 in Figs. 1, 2 and 3 to provide a rest for the

thumb of the operator as well as a stop which determines the position of the chisel with relation to the sheath by engagement with the end thereof. If so desired, the cutting member may be extended and doubled to provide a spring clip 16 shown in Figs. 4 and 5, which is formed to perform the functions of both the clip 12 and the stop 15 shown in Figs. 2 and 3.

10 The sheath is at its end opposite to that at which the cutting member is disposed, contracted as shown at 17, to snugly fit a pencil inserted therein, and the combined stop and thumb-rest 15 at the outer end of 15 the chisel is bent so that the distance between it and the thereto opposite end edge of the sheath is substantially equal to the diameter of the contracted portion 17. The object of this arrangement is to prevent the 20 cutting edge of the chisel from coming in contact with the surface of the pencil when the latter is moved lengthwise through the sheath as is shown in Fig. 3. The portion of the end edge of the sheath opposite to 25 the outer end of the cutting member is preferably hollowed, as shown at 18 to provide a seat across which the pencil is moved while it is being sharpened.

In the form shown in Figs. 4 and 5 the 30 longitudinally extending spring 9 is omitted and two oppositely disposed inwardly projecting springs 19 are formed integral with the sheath by incising the metal of which it is composed along semi-circular lines. The 35 springs 19 perform the same function as the springs 9 and 12, illustrated in Figs. 2 and 3, by engaging a pencil inserted into the sheath at opposite sides as is best shown in Fig. 5.

40 To point a pencil by means of my improved sharpener it is placed in contact with the seat 18 with its end extending into the mouth 4 in engagement with the cutting edge of the chisel 13. While the sheath is 45 held in one hand of the operator the thumb of the other hand which holds the pencil, engages the rest 15 formed at the outer end of the cutting member and the pencil is in this position, in which it is maintained by 50 pressure of the hand as well as by that of the springs 9 and 12, drawn longitudinally across the cutting edge of the chisel which thus removes the wood of which it is composed, it being understood that at the termination 55 of each outward longitudinal movement of the pencil, it is partially rotated to bring another portion in contact with the said edge. The fixed relation between the cutting edge of the chisel and the 60 pencil seat at the end of the sheath deter-

mines the fixed angle at which the pencil is invariably cut and which prevents breakage of the graphite, the springs while aiding in maintaining the pencil in engagement with the cutting edge while it is being pointed, also serve to clamp the sheath onto the pencil when not in use, and the formation of the ends of the article to snugly fit the pencil prevents the latter from coming in contact with the cutting edge when drawn longitudinally through the sheath.

The clips 12 or 16 provide a convenient medium for securing both the sharpener and the pencil to the pocket of a garment in which the latter is carried and it will be understood that by placing the sheath around the pointed end of the pencil, the article may be employed to protect the point thereof against breakage when not in use.

Having thus described my invention what I claim and desire to secure by Letters-Patent is:

1. In a pencil-sharpener, a sheath-member having a mouth adapted to receive the end of a pencil, and a cutting-member connected with said sheath and having at one of its ends a cutting-edge within said mouth, and at its opposite end, an enlarged portion which provides a thumb-rest beyond the corresponding end of the sheath, the distance between said rest and the opposite portion of the end-edge of the sheath being such as to snugly fit a pencil around which the sheath is placed, and the opposite end of the sheath being contracted to a diameter of similar dimension.

2. In a pencil sharpener, a cylindrical sheath member having two pairs of opposed lips and an intermediate support, and a cutting member placed upon said support and underneath said lips and having at one of its ends, a cutting edge, and at its opposite end, an enlarged portion which engages the end of the sheath to provide a combined stop and thumb-rest.

3. In a pencil sharpener, a sheath member having a mouth adapted to receive the end of a pencil inserted into an end of the member, and a cutting member connected with said sheath-member at its said end, and having a cutting edge adjacent said mouth, the opposite end of the sheath-member being contracted to fit a pencil around which it is placed.

In testimony whereof I have affixed my signature in presence of two witnesses.

JOHN L. ALKIRE.
